UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

CRANE ATTACHMENT.

Application filed May 8, 1923. Serial No. 637,594.

This invention has to do with crane or derrick attachments for large machines. In its preferred embodiment the crane attachment of the invention is mounted upon a concrete paver, so called today in the art to which it appertains, and embodying a mixing unit, a loading unit in the form of a skip, and a distributing unit which takes the mixed concrete and carries it to the sub-grade. The crane attachment of my invention is designed to lift a batch box which forms the body of an industrial car, from the truck of the car, shift it over the loading skip of the paving machine, dump the contents of the batch box into the skip and then return the box to the car. The purpose of the invention is to render rather highly automatic certain features of the crane attachment. To exemplify the foregoing, it may be noted that the novel features by which the foregoing object is attained include a crane mast which is so mounted that when the load of the batch box and its contents is imposed upon the mast the crane automatically carries the loaded batch box by swinging movement of the boom, to a position over the skip; a cable control for the batch box is then operated to actuate the cable thus causing a dumping of the batch box. When the batch box is dumped a spring peculiarly mounted in relation to the mast of the crane shifts the latter so as to carry the emptied batch box into a position out of the way of the loading skip which has now been filled. This last action is automatic and eliminates loss of time incident to manual operation, permitting immediate raising of the loading skip practically a moment after the batch box has been dumped to discharge into said skip.

In carrying out my invention I am using a double function spring for the purpose just previously mentioned. In other words, the spring I employ is a mast elevating spring by which the mast is raised automatically after the weight of a load is relieved therefrom, so that the foot of the mast will not be grounded except when a load is imposed upon the crane.

This last feature per se incident to a single function of the spring constitutes a separate invention of mine which is the basis of a separate application for a patent.

In the accompanying drawings Figure 1

is a diagrammatic plan view showing a concrete paver along side of an industrial railway, the crane attachment being illustrated in dotted lines as when it is being connected with a batch box of one of the railway cars, other dotted lines showing the swing of the crane boom over the skip to dump the box into the latter, and full lines showing the position to which the crane automatically moves to get out of the way of the skip and to a point adjacent to the railway as evident. 55

Figure 2 is an enlarged rear view of a portion of this machine which carries the automatic crane of my invention. The figure is a section on the line 2-2 of Fig. 6.

Figure 3 is a sectional view that brings out more clearly the arrangement and action of the spring in moving the mast about its vertical axis. The figure is a section on the line 3-3 of Fig. 6. 70

Figure 4 is another view, a partial front elevation of the spring showing more clearly its connection with the collar on the mast. 75

Figure 5 is a full rear elevation of the concrete paving machine and crane attachment with the boom of the crane swung laterally of the machine. 80

Figure 6 is a side elevation of the rear portion of the concrete paver, showing the batch box swung to a position above the skip, dotted lines illustrating the up and down movement of the mast and boom under the influence of the spring, and other dotted lines indicating the up and down movement of the batch box to automatically discharge the contents of the latter. 85

Figure 7 is a plan view of the rear end of the paver showing the special supporting means for the adjustable bracket in which the lower portion of the mast is adapted to slide and by which it is guided. 90

Figure 8 is a section on the line 8-8 of Figure 2. 95

Those acquainted with the art of concrete handling for the purposes of laying roads and pavements are familiar with the conventional type of concrete paver designated generally at A in the drawings. The machine comprises the mixer 1, the loading skip 2 and the boom and bucket or other type of distributor 3. 100

The industrial railway illustrated in Figure 1 is a conventional type, and is generally indicated at B, its hopper cars are designated 105

C and are of the bottom dump class, or in other words, are emptied with bottom dumping doors 4, seen best in Figure 6.

My crane attachment in most of its main features of construction has heretofore been put into extensive use and found very efficient in operation. The attachment comprises the mast 5, the upwardly swinging boom 6 adapted to swing horizontally or laterally with the mast 5 as an axis, grapple means including an upper cross head 7 and a lower cross bar 8, and a hoisting cable 9 which is connected at one end with the cross bar 8, passes around sheaves 10 at the upper end of the boom and around a sheave on the head 7. The cable 9 extends to a hoist drum 11, as seen in Figure 6 to best advantage. The boom 6 is limited in its outward and downward movement by a chain 12 which permits of pulling the boom inward toward the mast 5 under certain conditions of service, and not particularly relevant to the present invention. The mast 5 is pitched at a slight angle to the vertical, being supported by a guide bracket 13 through which the lower portion of the mast 5 passes, the lower end of the mast having a loosely swinging foot 14 of now known construction. At its upper end the mast 5 is connected with a spring 15, preferably of the coiled type, one end of which is attached to the upper portion of the frame-work of the paver A, and the other and lower end of which is attached to a clamp collar 16 on the mast.

Normally the tendency of the spring 15 is to lift the mast 5 to substantially the position of Figure 5, permitting a moving downward or grounding of the mast, as shown in Fig. 6, when a load is imposed upon the crane attachment, as per the illustration of said last named figure.

The slight inclination of the mast 5 from the vertical is the means heretofore proposed by me whereby the load which may be grappled and raised by the cross bar 8 and the cross head 7, the latter with its chains 17 and hooks 18, will be caused to automatically shift from a position say at right angles to the machine A, as seen in Fig. 1, to a position above the loading skip 2 of said machine, owing to the automatic rotation of the mast incident to the gravitational action of the load imposed thereon. When the load, in this instance the batch box C, reaches its position above the skip 2, the operator winds in the cable 9 and thereby raises the cross bar 8 which is engaged with loops 19 at opposite sides of the body of the batch box C, and also raises the cross head 7, the hooks 18 of the chains 17 of which are engaged with loops 20 of slides 21 on the opposite sides of the batch box. The slides 21 connect with the doors 4. When the batch box C has been raised a sufficient distance to bring the sheave block 22 of the cross head 7 into engagement

with a vertical stop bar 23 depending from the upper end of the boom 6, the movement of the doors 4 of the batch box ceases, but the continued pull on the cable 9 raises the body of the batch box. This is illustrated in Figure 6 in dotted lines, and the relative movement of the body of the batch box C and the doors 4 causes opening of the latter and dumping of the box contents into the skip 2. The load on the crane attachment is materially relieved incident to the foregoing operation of dumping the batch box C, and the spring 15 has its connection with the collar 16 so located that upon emptying of the batch box the spring tends to rotate the mast 5 in a direction opposite to its movement previously described, due to its inclination to the vertical, thereby shifting the boom 6 to a position about that indicated in full lines in Fig. 1. In such full line position it will be apparent that the boom is out of the way of the skip and moves to that position carrying with it the batch box under the influence of the spring 15, and without any manual operation the batch box is carried clear of the skip 2 and in position not interfering with movement of the train C.

The inhaul on the cable 9 is intended to pull the boom 6 in towards the mast under some conditions, not relevant to this invention. Likewise it is notable that the mast 5 is grounded when the parts 8 and 18 are engaged with the batch box parts and the weight of the batch box is transferred to the crane attachment. Thus the load of supporting the weight of the batch box and its contents is not received upon the paving machine but is largely carried by the foot member 14 of the mast 5 and the subgrade upon which the machine A travels.

The peculiar off-set disposition of the point of connection of the spring 15 with the arm of the clamping collar 16 gives rise to the advantages of certain automatic movement of the emptied batch box, to a position out of the way of the skip. It is furthermore notable that the cable 9 really performs several functions, because under its influence as a single operating member, the batch box is first hoisted off of the industrial car. As soon as the batch box is clear of the car truck under the influence of the cable the swinging movement of the crane is initiated under the influence of gravity so that the batch box is carried over the skip 2. Then under the influence of the same cable the box is dumped and the dumping of the load relieves the influence of gravity so that spring 15 will overcome this force and swing the box into a position clear of the skip and tram from which it may be moved readily by hand or other means to swing the emptied batch box over the car truck where it may be lowered upon the truck by the same cable 9. Thus the cable

9 does five or six things, considering actions of the parts initiated under the influence of its operation to be actions which are controlled by the cable. This is a very desirable thing owing to the simplification of operation of the machine thereby attained.

The chain 12 is preferably attached at its inner end to the upper bracket 13^a at the top of the framework of the machine, which 10 upper bracket forms the upper guiding means for the mast 5. The bracket 13^a may be formed with a flange provided with a series of openings therein designated 13^b, so that the chain 12 may be adjusted slightly 15 at its point of connection with the framework, this adjustment being adapted to influence the swinging movement of the crane that is more fully presented hereinafter.

The lower bracket 13 which supports the 20 mast 5, and forms a guide for the latter, is mounted peculiarly in that it is slidable forwardly or rearwardly upon an arm 13' which projects rearwardly from the frame of the machine and forms a part of a main 25 bracket carrier or slide 13''. As seen in Fig. 7, the bracket 13 may be slid rearwardly or forwardly on the arm 13' by a screw adjuster 24 having a handle 25. Likewise the carrier 13'' is susceptible of a lateral back 30 and forth movement respecting the frame of the machine thru the provision of a similar screw 26 having a handle 27. The bracket carrier 13'' may be slidably mounted upon the frame of the machine in any suitable 35 manner as by being grooved to receive the head of an outstanding lug 28 carried by the channels that form the framework of the machine. In a like manner the arm 13' may have a groove which receives a head 29 ex- 40 tending from the bracket 13. The heads 28 and 29 may be of T form in cross section and of any substantial construction to interlockingly connect with the parts with which they have sliding co-operation.

45 The special purpose of the mounting of the bracket 13 as I have thus described it, is to accommodate for different conditions under which a paver with which I may use my crane attachment, may be employed. 50 Thus under modern road construction, super-elevation around curves is becoming more and more required. This elevation in Illinois is one inch to the foot, so that with an eighteen foot road the outer edge of the 55 curve is eighteen inches higher than the inner curb. Naturally the subgrade on which concrete is laid has a corresponding elevation with that of the final pavement. Obviously sloping subgrades on which pavers 60 have to travel affect the action of a crane attachment such as embodied in this invention, especially where the mounting of the mast 5 controls an actual operation of the boom in swinging. On the above account, 65 adjustment of the supporting means for the

70 mast 5, and the bracket 13 is desirable and advantageous, enabling a nicety of positioning of the mast in relation to the vertical so that it will function properly and definitely to accomplish the results that have hereinbefore been explained. The adjustment 75 on the bracket 13 is double so as to accommodate not only for adjustment of the mast to a proper vertical position to obtain its automatic swinging movement, but to create 80 a proper stability of the mounting of the mast when the framework of the paver is somewhat inclined due to the fact that the paver is either ascending or descending a more or less steep grade. In mountainous 85 regions very steep grades are encountered in fact in the road construction work, and a forward and rearward adjustment of the bracket 13 on the arm 13' is a very excellent 90 provision for a corresponding adjustment of the mast 5 under the conditions just above referred to, and such adjustment is necessary so that the other parts of the crane will function properly.

I wish to also explain that while I have 95 illustrated my cable control for the dumping of the batch box as involving an operation of elevating the batch box to effect the dumping operation, conditions may require that the box be lowered for dumping. 100 Where hopper cars are used the lifting of the batch box is allowable for dumping, but if the boxes be carried by a motor vehicle it is best to dump the box as it is lowered above the skip. Under these conditions the 105 relative movement of the box and its bottom dump doors may be controlled by the cable after the manner of limiting the downward movement of the box and permitting an additional downward movement of its 110 doors, a method reverse to that described herein, and adapted to be performed by means set forth in the co-pending application of E. L. Tranaas, Serial #572,546, filed July 3, 1922.

110 Since the above invention specifically does not form a part of my present invention, it is not illustrated, it merely being my object to set forth that my cable control may operate to dump the batch box either during 115 the upward or downward movement of the latter, and my claims are to be read in the light of this explanation.

Having thus described my invention what I claim as new and desire to secure by Letters Patent is,

1. In combination, a support, a crane thereon embodying a horizontally swinging boom, a load engaging apparatus on said boom, a mast supporting the boom and mounted out of true vertical line so as to automatically cause swinging of the boom in one direction, cable operating means for the load engaging apparatus for raising a load and thereby initiating said swinging move- 130

ment of the boom in one direction, and means for causing a swinging movement of the boom in another direction, adapted to have its operation initiated by action of said cable means.

2. In combination, a portable support, a crane attachment thereon comprising a mast vertically movable on said support, a foot for the mast adapted to be grounded by the weight of a load imposed upon the attachment, and a device coacting with the mast for raising it from a ground position and for at the same time turning the mast about its vertical axis.

3. In combination, a support, a crane attachment therefor including a mast, a swinging boom carried by said mast, a load engaging apparatus connected with said boom, cable means connected with said apparatus, the crane attachment being mounted to automatically swing to unloading position from loading position as an incident to imposition of a load upon the load engaging apparatus, means to operate the cable means to impose a load upon said apparatus and thereby initiate the automatic movement of the attachment to unloading position, means to move said crane attachment toward its loading position after discharge of the load imposed on said apparatus, said last mentioned means comprising a spring for swinging the attachment and for raising the attachment vertically relatively to the ground.

4. In combination a portable support, a crane attachment thereon comprising a mast vertically movable on said support, a foot for the mast adapted to be grounded by the weight of a load imposed on the attachment, a boom extending from the mast for swinging movement, the mast being pitched in such a manner as to tend to swing the boom to an unloading position automatically, and a device coacting with the mast for raising it from a ground position and for swinging the boom in a direction opposite its automatic swinging movement toward unloading position.

5. In combination, a portable support, a crane attachment thereon comprising a mast vertically movable on said support, a foot for the mast adapted to be grounded by the weight of a load imposed on the attachment, a boom extending from the mast for swinging movement, the mast being pitched in such a manner as to tend to swing the boom to an unloading position automatically, a device coacting with the mast for raising it from a ground position and for swinging the boom in a direction opposite its automatic swinging movement toward unloading position, combined with a load engaging apparatus on the boom, and cable means for operating said apparatus to impose the weight of a load on the attachment and initiate the movement of the mast to swing the

boom toward an unloading position, said cable means being adapted to operate the load engaging apparatus to render effective the means for swinging the boom from its unloading position.

6. In combination, a support, a crane thereon comprising a mast and a swinging boom, the said crane being so mounted that when a load is imposed thereon it will swing to an unloading position, and spring means for moving the said crane toward a loading position when the load imposed on the crane is released.

7. In combination, a support, a crane thereon comprising a mast and a swinging boom, the said crane being so mounted that when a load is imposed thereon it will swing to an unloading position, and spring means for moving the said crane toward a loading position when the load imposed on the crane is released, the crane being mounted for a vertical movement to ground it and maintain it off the ground and said spring being so connected to the crane as to raise it from the ground.

8. In combination, a support, a crane mounted thereon for swinging movement, a load engaging apparatus on the crane, and a single cable connected with said load engaging apparatus and operable to impose a load on the crane and discharge the load from the crane, the crane being constructed to swing in one direction when a load is imposed thereon by the cable, means for swinging the crane in another direction as an incident to the discharging of the load from the crane by the cable, the crane being movable so as to ground it and embodying a boom, the said cable being adapted simply to swing the boom toward the support on which it is mounted, and the other means for swinging the crane being adapted to raise the crane clear of the ground.

9. In combination a portable support, a crane attachment thereon comprising a mast vertically movable on said support, a foot for the mast adapted to be grounded by the weight of a load imposed on the attachment, a boom extending from the mast for swinging movement, the mast being pitched in such a manner as to tend to swing the boom to an unloading position automatically, a device coacting with the mast for raising it from a ground position and for swinging the boom in a direction opposite its automatic swinging movement toward unloading position, and a bracket device connected with the support for lateral adjustment to maintain the mast normally in pitched position and forming a supporting and guiding means for the mast.

10. In combination, a support, a crane thereon embodying a horizontally swinging boom, a load engaging apparatus on said boom, a mast supporting the boom and mounted

- out of true vertical line so as to automatically cause swinging of the boom in one direction, cable operating means for the load engaging apparatus for raising a load and thereby initiating said swinging movement of the boom in one direction, means for causing a swinging movement of the boom in another direction, adapted to have its operation initiated by action of said cable means, 10 the load engaging apparatus including parts operable by said cable for discharging the load engaged by the apparatus, thus initiating the said movement of the boom in the opposite direction stated, and a bracket adjustably mounted on the support for longitudinal and lateral movement and co-operating with the mast to support the latter and cause it to assume its position out of true vertical line.
- 15 11. In combination with a support, a crane attachment comprising a swinging member, a load hoisting and supporting device thereon, said device including a cable, the crane attachment including a boom for causing the said device to swing from a load-

ing position to an unloading position, means to operate the cable of said device to initiate the movement of the last mentioned part and to cause an unloading operation of said device, and means supporting the crane attachment upon the said support adapted for longitudinal and lateral adjustment to accommodate for proper functioning of the crane attachment when the support is carried by subgrades inclined either laterally or longitudinally.

12. In combination, a portable machine comprising a framework, a crane attachment carried thereby and embodying a boom, cable hoisting means associated with said boom for raising loads to be handled by the attachment, a bracket co-operating to support said crane attachment on the portable machine, and means for adjusting said bracket longitudinally of the framework of said machine and also laterally of said framework.

In testimony whereof I affix my signature.

ERICH H. LICHTENBERG.
